ABSTRACT OF THE DISCLOSURE

This invention relates to a frequency synthetizer for use in a railway signalling system in which a cable located in each zone of a railway line is fed by currents of different frequencies depending on the condition of the line in the zone following the zone where the cable is located. The frequency synthetizer comprises a chain of elements in a closed loop including a number of oscillators of different frequencies each of which is connected to a filter tuned to the corresponding frequency through a gate which opens only when a signal voltage, is provided by a signalling apparatus located in the zone following the zone under consideration. The outputs of the filters are fed to the cable through a summing amplifier and a power amplifier. The output of the power amplifier is applied to a comparison circuit which delivers an output signal only when the output voltage of the power amplifier is between two predetermined values. This output signal controls the opening of a gate which permits a pilot oscillator to drive an amplifier which feeds the above-mentioned frequency oscillators. In addition, means are provided to initially open the gate associated with the pilot oscillator to initiate the operation of the circuit.

This invention relates to a frequency synthetizer for transmission of information to railway vehicles.

It has been established that a train running at a speed of 200 km./h. requires a distance of at least 3 km. to come to a stop. The normal signalling methods which are conceived for trains whose speed does not exceed 160 km./h. do not permit to warn in time an engine driver of the presence of a stop signal. Nevertheless, in order to permit trains to run at 200 km./h. on railway lines equipped with the normal signalling methods without having to modify it, it has been proposed to position a special signalling device in the train which responds to the required conditions. For this purpose, a cable in the shape of a loop has been installed between the rails in each railway zone. Such cable is energized by currents of different frequencies according to the condition of the signals at the entrance of the zone following the zone under consideration. This loop induces a voltage in the train which determines the operation of the local signalling system. Thus, in a zone preceding a red light, a first frequency is fed to the cable to signal that the train must be stopped at the end of the zone. In the preceding zone, at the end of which is positioned an amber light, a second frequency indicates that when approaching the light the speed must be reduced under 160 km./h. In the two zones further ahead, where green lights are located, a third and a fourth frequencies corresponding to 180 and 200 km./h. respectively are fed to the cable.

The object of the present invention is an apparatus called frequency synthetizer whose function is to provide the cable of each zone with a current of a suitable frequency in accordance with the conditions on the line and this, with a maximum amount of security. The frequency

2

synthetizer in accordance with the invention comprises a chain of elements in a closed loop including a number of oscillators of different frequencies each of which is connected to a filter tuned to the corresponding frequency through a gate which opens only when a signal voltage is provided by the apparatus controlling the signal located in the zone following the zone under consideration. This voltage appears when the conditions on the railway line require the feeding of the cable of the zone at the said frequency. The outputs of the filters are applied to the input of a summing amplifier which is connected to a power amplifier feeding the cable. The output voltage of the power amplifier is applied to a comparison circuit which delivers an output signal only when this output voltage is between two predetermined values. This output signal controls the opening of a gate which permits a pilot oscillator to drive an amplifier which feeds the above-mentioned frequency oscillators. In addition, means are provided to initially open the gate associated with the pilot oscillator to initiate the operation of the circuit.

The invention will now be described with reference to the drawings which relate to a particular embodiment of the invention. In the drawings:

FIG. 1 indicates schematically the frequencies applied to the cables located in the successive zones corresponding to the represented positions of the signals; and

FIG. 2 illustrates a frequency synthetizer in accordance with the invention.

As indicated in FIG. 1, in a section preceding a red light a frequency F_{00} is fed to the cable to signal that the train must be stopped at the end of the zone. In the preceding zone, at the end of which is positioned an amber light, a frequency F_{16} indicates that when approaching the light the speed of the train must be reduced under 160 km./hr. In the two zones further ahead, where green lights are located, frequencies F_{18} and F_{20} correspond respectively to 180 and 200 km./h. respectively.

FIG. 2 illustrates a frequency synthetizer associated with the control equipment of a signal located down a railway zone equipped with a transmitting cable K. This signal comprises lights R, J and V which are respectively red, amber and green and fed by a source of alternative current AL through the contacts of relays R_v and R_a which, with a third relay R_p , are controlled by logic circuits not shown. Relay R_v is energized when the zone down the signal is free and relay R_a is excited when the zone down the preceding zone is also free. Relay R_p is energized when a third zone past the two preceding zones is also free. The positions of the contacts of the relays R_v , R_a and R_p shown in FIG. 2 correspond respectively to R_v released and R_a and R_p energized.

The release of relay R_v determines the energization of light R and of transformer T_r . The release of relay R_a combined with the energization of relay R_v light up light J and energize transformer T_j . The energization of relays R_a and R_v lights up light V. Finally, the energization and the release of relay R_p can permit the energization of transformers T_p and T_v respectively. The secondary windings of transformers T_r , T_j , T_v and T_p provide information signals r , j , v , and p which involves the necessity of feeding cable K with frequencies F_{00} , F_{16} , F_{18} and F_{20} respectively. It is understood that only one of the above information signals is generated at a time. The synthetizer comprises four oscillators F_{00} , F_{16} , F_{18} and F_{20} operating, when energized, at the frequencies designated above by the same notations. Oscillators F_{00} , F_{16} and F_{20} are connected to filters f_{00} , f_{16} , f_{18} and f_{20} respectively through corresponding gates P_{00} , P_{16} , P_{18} and P_{20} . These gates open only when information signals r , j , v , or p are applied to them. They may be relays, magnetic static elements, or transistor circuits. The outputs of the different filters are connected to the input of an adding

amplifier AS which drives a power amplifier AP whose output feeds cable K through a transformer T_1 . The output voltage of amplifier AP is applied, after having been rectified, to the input of a comparison circuit C which delivers an output signal only when the above voltage lies between two predetermined values. Such a comparison circuit is disclosed in U.S. patent application No. 591,546 filed in the name of the present assignee. The output signal of circuit C opens a gate S which permits the energization, by means of a pilot oscillator O, of an amplifier AA which feeds the different oscillators F_{00} , F_{16} , F_{18} and F_{20} through a transformer T_2 . A push-button switch B permits the opening of gate S in the absence of an output signal from comparison circuit C and starts the synthesizer circuit which continues to operate when push-button switch B is released assuming that the circuit works properly. In the example illustrated in FIG. 2, information signal r only is present and opens gate P_{00} so that oscillator F_{00} which is fed by amplifier AA in turn feeds filter f_{00} whose output causes the energization of cable K through amplifiers AS and AP on the one hand, and on the other hand the energization of comparison circuit C which opens gate S permitting oscillator O to energize amplifier AA which feeds oscillator F_{00} . Consequently, the synthesizer circuit works in a closed loop and the breakdown of one of its elements causes the stopping of the operation. In particular, an oscillator cannot control the energization of the cable unless it is connected to a filter tuned to the same frequency through its associated gate. Consequently, a protection is secured against any drifts of the oscillator or the filter because it is recognized, and this is reasonable, that two breakdowns cannot happen simultaneously and that the equipment will take all its configurations between two successive breakdowns. This is true because it happens at every passing of a train and that, on the other hand, the average time interval between breakdowns in an equipment of this type is in the order of six months to one year. The operation in a closed loop causes the stopping of the apparatus at the first breakdown which prevents a second breakdown from compensating the first one. For example, if a drift of oscillator F_{00} did not stop the equipment, it would not be impossible that f_{00} starts also to drift towards the modified frequency off oscillator F_{00} in which case the cable could be fed at a frequency different from the normal frequency of oscillator F_{00} .

The elements constituting the above frequency synthesizer may be built up in a known manner, furthermore, various modifications may be effected without departing from the scope of the present invention.

We claim:

1. A frequency synthesizer for use in a railway signalling system in which, in each zone of a railway line, signals of different frequencies in accordance with the state of signalling lights at the entrance of the zone following the zone under consideration are inductively transmitted to the trains, comprising a chain of elements in a closed loop including:

(a) a cable forming a loop located along the railway line in each zone and having two terminals;

- (b) a plurality of oscillators operating at different frequencies;
  - (c) a plurality of filters tuned to the frequency of said oscillators;
  - (d) a plurality of gates, each gate interconnecting an oscillator to an associated filter, each gate being opened by a signal from the railway zone following the zone under consideration and such signal appearing when the railway line conditions require the energization of the cable of the zone under consideration at a predetermined frequency;
  - (e) amplifier means connected to the output of said filters for energizing the terminals of the cable;
  - (f) a comparison circuit connected to the output of said amplifiers adapted to generate an output only when the output of said amplifier means is between two predetermined values;
  - (g) a pilot oscillator;
  - (h) gate means interconnecting said pilot oscillator to said plurality of oscillators, said gate means being controlled by the output of said comparison circuit; and
  - (i) means for initially opening said gate means to start the operation of the synthesizer circuit.
2. A synthesizer circuit as defined in claim 1, further including a signalling system comprising a plurality of relays which are selectively operated in accordance with the line conditions in the zone following the zone under consideration to provide a signal to each of said plurality of gates.
3. A synthesizer circuit as defined in claim 2, wherein said signal is derived from a source of alternating current through the contacts of said relays.
4. A synthesizer circuit as defined in claim 3, further including a light for indicating the conditions of the line in the zone following the zone under consideration.
5. A synthesizer circuit as defined in claim 3, further including a transformer for coupling said source of alternating current to each of said plurality of gates.
6. A synthesizer circuit as defined in claim 1, wherein said amplifier means includes a power amplifier.
7. A synthesizer circuit as defined in claim 1, further including a transformer for coupling said amplifier means to said cable.
8. A synthesizer circuit as defined in claim 1, further including an amplifier and a transformer connected to the output of said amplifier for coupling said gate means to said plurality of oscillators.
